1 Claim. (Cl. 95—75)

This invention relates to photographic printing and more specifically to printing from kinemagraphic films.

Owing to variations in actinic conditions during the exposure of various sections comprising most kinemagraphic films and to the resulting variable density of the film negative, it is desirable, in order to obtain a print whose light level does not vary considerably throughout its length, to compensate for this varying density.

Various methods have been employed for this purpose hitherto, for example, a variation in the current passed through an electric lamp providing light for printing, the variation being appropriate to the compensating light value required; this method has the drawback that change of brilliance of the lamp alters the colour values emitted in addition to merely altering the intensity of the light.

Another prior method is to cause the printing light to pass intermittently through a film negative and a control film which latter has been formed in sections mechanically attached together to form a strip or length of film, the individual portions of which have the required degree of obscuration. This method has the drawback that it can only be used with an intermittent step movement printer since the control film must be moved to its next position during the "shutter covered" period. Intermittent step movement printers cannot be run faster than approximately 40 feet per minute.

Another prior method is to employ a mechanical "gate" the width of opening of which has to be set by hand for each individual section of the film. This method has the drawback that the speed of printing is controlled by the skill of the operator and consequently in practice the maximum speed of transit of the film during printing cannot be made to exceed about 60 feet per minute.

A further prior method is to use a translucent strip which is moving continuously during the printing operation at one fourth the speed of the negative film. Strips of each width are made photographically in long lengths, these being stored for future use. Strips of the required widths are then joined in suitable lengths in synchronism with the picture negative by winding over a synchronising device. This method entails much handling of the valuable negative film. Furthermore, owing to the fact that the widths vary by only a few thousandths of an inch and that the photographic fog is liable to vary from time to time in the manufacture of the lengths of

translucent strip uniformity of results is most difficult of achievement.

The main object of the present invention is to provide an improved method and means for taking photographic prints of kinemagraph films with great rapidity the prints possessing substantially uniform light value throughout, irrespective of variation in density of different sections of the film.

- 10 Referring to the accompanying drawings: Figure 1 is a front view of part of one convenient form of apparatus embodying the present invention.
- 15 Figure 2 is a side elevation thereof.
- 18 Figure 3 is an enlarged plan view.
- Figure 4 is a vertical sectional view on the line A—A of Figure 3, whilst
- Figure 5 is a vertical sectional view on the line B—B of Figure 3.
- 20 In carrying the invention into effect according to one convenient form illustrated by way of example in Figures 1 to 5, we provide an optical system projecting a beam of light from a lamp 42 through a lens 43 and then vertically upwards
- 25 through a prism a, through a further prism b and thence through a slot c over which the kinemagraph film d from which a print is to be taken, and the print e itself are caused to travel. The film together with the print are carried on spools
- 30 and are fed forward together at a constant speed.

Interposed in the path of the beam is a control film f carried on spools 30, 31 and furnished with shift apparatus described below. The control film comprises a strip of film furnished at the centre with a series of adjoining photographically produced translucent sections forming a continuous strip running from end to end of the film. The widths of the various sections, however, vary throughout the length of the film in accordance

- 40 with the desired degree of obscuration of the beam and the number of sections is equal to the number of different light levels in the negative.
- Whilst printing of a particular section of the kinemagraph film d in which the light value is
- 45 substantially constant is taking place, the control film f is stationary and a predetermined degree of obscuration of the beam results, but when a succeeding section of the film is being printed in which, say extra printing light is required to
- 50 compensate for increased density of this section, a wider-apertured frame or section in the control film strip will have been shifted into place in the path of the light beam.

The shift mechanism for the control film f

55 comprises a constantly running shaft g upon

which is rigidly mounted an electromagnetic clutch *h*, the armature *j* of which comprises a disc normally pressed lightly by a spring (not shown) out of contact with the associated clutch *b*.

The spindle is mounted in bearings *k m* in a frame *o* and has a collar *v* rigidly mounted near one of its ends. The clutch *h* carries slip rings *p* contacting with brushes *q* by means of which current is supplied to the coil of the clutch when it is desired to cause the armature *j* to be picked up and rotated with the clutch body. The armature *j* is rigid within a collar *r* on a sleeve *s* mounted in bearings *t u* on the shaft *g*.

The sleeve *s* carries loosely two disc members *w, w₁*, and each of these disc members has an integral collar *x, x₁* and is furnished with a pin *y*; the pins are connected by tension springs *z* with a radial pin *2* rigidly fixed to a sleeve *s*. The disc members are cut away at one part of the periphery to form projections *3, 3a*, coacting with stop members *4, 4a* formed at one end of a pair of spring-urged see-saw levers *5, 5a* pivoted at *6*. The radial pin *2* projects through slots in the collars *x, x₁*, one of which slots is shown at *9* in Figure 4. The sleeve *s* carries rigidly a driving disc *10* and integral collar *11*, the disc being furnished with two radial teeth *12* and depressions *13* for engaging teeth *14* on a driven member comprising a disc *15* and integral collar *16*. The disc *15* is coupled by pins *19* and spring-urged plungers *20* to a further disc *21* having further teeth *18* and the disc *10* carries a projecting pin *17* for cooperating with spaces between said further teeth *18*.

The disc *15* is fast on the driven shaft *22* whilst the disc *21* is loosely mounted thereon. The collar *v* on the shaft *g* acts as an abutment for a spring *23* abutting a D-washer *24* whereby axial pressure is applied to a friction washer *25* abutting a collar *26* screwed to the sleeve *s*.

The shaft *22* is mounted in bearings *27, 28* in the frame *o* and carries rigidly a toothed wheel *29* having, say, 50 teeth for engaging marginal perforations in the control film *f* which is carried on spools *30, 31* mounted on members *32, 33* respectively. These members *32, 33* are rigid on shafts *34, 35* carrying gear wheels *36, 37* driven by a common gear wheel *38* rigid on the shaft *22*.

It is preferred to employ a large area of control film for each section and to avoid any joint or obstruction, thus ensuring that any minute spots or imperfections in the translucent part of each section of the control film do not affect the printing light intensity.

The length of each section of the control film conveniently embraces five marginal perforations, the perforations being engaged by the teeth of wheel *29*.

A pair of spring-urged levers carrying rollers *39, 39a* at their free ends are provided, the rollers engaging one edge of the kinematograph film *d* and the levers serving to control electric circuits for actuating two solenoids *40, 41*. The solenoid *40* controls the see-saw lever or armature *5* to release the projection *3* whilst the solenoid *41* controls a similar armature *5a* to release the projection *3a*. The edge of the film *d* engaging the roller *39* is furnished with shallow notches at appropriate positions along its length so that as the film moves past the roller the latter enters the individual notches and thus causes the spring-urged levers to cant and so close momentarily the circuits of the solenoids *40, 41* when shift is to take place.

In operation, the driving shaft is caused to rotate continuously in one or other direction according to whether the film *d* and print *e* are moving from right to left in Figure 1 or vice versa, but so long as the control film *f* is desired to remain stationary to intercept a particular fixed degree of obscuration in the path of the light beam, the armatures *5, 5a* are held stationary by the springs associated therewith and the particular projection *3, 3a* is held by its latch *(4)*; the Maltese spur toothed gearing *10, 15* and the 50-toothed wheel *29* thus remain stationary.

Assuming the rotation of the shaft *g* to be in clockwise direction as viewed from its driven end in Figure 3, then owing to the friction introduced by the washer *25* the sleeve *s* and the members thereon will tend to rotate clockwise. They will, however, be prevented from movement by the latch *4* lying in the path of the projection *3*.

When a notch in the edge of the kinematograph film *d* permits the control roller *39* to drop thereto, a circuit is closed to energize the clutch *h* and also to actuate stop latches. The armature or clutch plate *j* will thus be brought into frictional driving contact with the clutch *h* and will commence to rotate. The sleeve *s*, disc *10* and discs, *w, w₁* will also commence to rotate and in due course the pin *17* on disc *10* will strike one of the teeth *18* and thus load the mechanism *19, 20*. After a short period of time the teeth *12* engage the teeth *14* and the disc *15* will rotate through $\frac{1}{10}$ of a revolution; the disc *15* in turn will rotate the wheel *29* through a corresponding amount, thus feeding forward the control film *f*. The sleeve *s* continues to be driven forwards by the friction washer *25* until the projection *3* meets the stop *4*, the shock of impact being absorbed by the springs *z*. The teeth *18* in conjunction with the pin *17* serve to limit the movement of the disc *21* thus ensuring that the wheel *29* comes to rest in accurately predetermined positions after each progression.

The members *32* and *33* are partially rotated by gear wheels *38, 36* and *37* as the movement of the shaft *22* takes place.

After the control roller *39* has been forced outwards to resume its normal position against the edge of the kinematograph film, no further movement of the control film *f* takes place until the next notch in the edge of the film *d* comes into register with the roller *39*.

The feeding motion of the control film *f* will take place very rapidly indeed owing to the action of the continuously running clutch *h* and the associated mechanism, the shift in practice being completed during the interval occupied in the kinematograph film *d* being moved forwards from one frame to the next.

Owing to the control film strip changing from one section to another abruptly with no obscuring of the light, the effect, when a change is taking place, is that of a fade from one light value to another, and owing to the change is made very rapidly and taking place at a frame line the light change is not noticeable in the final projection print.

The provision of the resilient mechanism *2, 2₁* and *20* facilitates the rapid action desired whilst reducing noise and wear of the mechanism.

The driving shaft *g* may be operated in a clockwise or counter-clockwise direction as desired according to the direction in which it is desired to pass the kinematograph film *d* and print *e* through the apparatus for printing and one or other of the rollers *39, 39a*, the stops and projec-

tions 3, 3a are operative according to the selected direction of rotation. Whilst in the above example a notch in the edge of the film negative is employed for controlling the shift of the control film, other means may be employed. For instance, the thickness of joints in the negative or metal staples suitably fitted to the negative may be utilized to actuate electrical contacts to the circuit of the clutch *h* and of the solenoids 40, 41.

It will be appreciated that in accordance with the present invention photographic fog occurring during the formation of the control film is distributed over the whole of the control film and thus has only a negligible effect upon the controlling effect produced.

We claim:

Apparatus for printing a motion picture film from a negative having a plurality of sections of different light levels embodying means for moving the positive and negative films with a uniform 20

motion, a source of light of fixed intensity, a film strip mask interposed between said films and said light source, a plurality of translucent sections of uniform density but different widths on said mask equal in number to the number of light levels in the negative, intermittently operated shifting mechanism for said film strip mask comprising switch contacts actuated by said negative, a constantly rotating shaft controlled by said switch contacts, a driven member and an electromagnetic clutch between said driven member and said shaft, and wherein a plurality of mechanical stops co-acting with said shifting mechanism and an electromagnetic relay co-acting with said mechanical stops are provided, and means for starting and stopping said shifting mechanism at intervals dependent upon the lengths of individual translucent sections on said mask.
